(57) **CLAIM**

The ornamental design for a video-conferencing booth with integrated table and seats, as shown and described.

DESCRIPTION

1.-3. Video-conferencing booths with integrated tables and seats

1.1 is a front perspective view of a first embodiment.

1.2 is a front view.

1.3 is a front perspective view showing the opposite side.

1.4 is a rear perspective view.

1.5 is a rear view.

1.6 is a side view.

1.7 is a top view.

1.8 is a rear perspective view showing the opposite side.

1.9 is an opposite side view.

2.1 is a front perspective view of a second embodiment.

2.2 is a front view.

2.3 is a front perspective view showing the opposite side.

2.4 is a rear perspective view.

2.5 is a rear view.

2.6 is a side view.

2.7 is a top view.

2.8 is a rear perspective view showing the opposite side.

2.9 is an opposite side view.

3.1 is a front perspective view of a third embodiment.

3.2 is a front view.

3.3 is a front perspective view showing the opposite side.

3.4 is a rear perspective view.

3.5 is a rear view.

3.6 is a side view.

3.7 is a top view.

3.8 is a rear perspective view showing the opposite side.

3.9 is an opposite side view.

The broken lines show portions of the article that form no part of the claimed design.
